METHOD OF ORIENTING WHIPSTOCKS

Gottdank L. Kothny, Strafford, Pa., assignor to
Sperry-Sun Well Surveying Company, Philadelphia, Pa., a corporation of Delaware

Application September 27, 1933, Serial No. 691,253

4 Claims. (Cl. 255—1)

This invention relates to the drilling of wells and has particular reference to a method of orienting a whipstock designed to guide a drill in a definite direction as is necessary, for example, in straightening a crooked well.

As is well known, many wells, particularly those produced by rotary drilling, deviate very considerably from the vertical at even moderate distances below the surface, such deviations being apparently due to lack of uniformity in the soil through which the drill is passing and being particularly noticeable in the case of rotary drilling since the rotation of the drill stem appears to promote the production of a tortuous hole. If a bore hole deviates to a substantial degree from the vertical it may entirely miss the locality which is believed to contain oil. Once a bore hole begins to deviate from the vertical little can be done in the way of controlling the drill from the surface to cause it to become straight. Accordingly, it is the practice to insert within the bore hole a whipstock having a guiding surface at an angle with the axis of the bore hole to direct the drill in the desired direction to reach its objective. Obviously it is necessary to properly orient the whipstock and check the orientation to insure that a proper correction of the direction of the bore hole will be made.

The orientation of a whipstock necessarily involves a knowledge of the path of a bore hole so that a preliminary survey must be made to find the direction and position of the lower end of the hole.

Various methods of orienting whipstocks are known, a typical one being described in the transactions of the Institute of Mining and Metallurgy (1911—1912, pages 481 to 489). The methods such as that described in this publication are comparatively difficult to carry out and are not likely to lead to an accurate positioning of the whipstock, unless a check of the true position of the whipstock is made by means of an accurate well surveying instrument of gyroscopic type, magnetic instruments being affected by magnetic materials, casings, etc. Carrying out any of the known processes, however, is quite difficult by reason of the various manipulations involved, so that they are impractical.

In the process described in the above publication, the whipstock is lowered on the end of a drill stem, being secured to the drill stem by means of soft metal rivets which can be sheared off to eventually leave the whipstock in position. Since this is the desirable manner of lowering the whipstock it suggests the possibility of orient-

ing the whipstock by orienting the upper end of the drill stem if the drill stem is made of sections which are lined up with each other in a known fashion. Attempts have been made to so orient whipstocks under the assumption that if a certain point at the upper end of the drill stem, consisting of aligned sections, will point north when a corresponding point at the lower end of the drill stem points north, assuming the drill stem to be straight, then this correspondence in azimuth of the two points will be maintained when the drill stem is located within a crooked bore hole. This, however, is incorrect. Due to the effect of tortuosity even though there is no torsional stress upon the stem about its axis at any location along its length, nevertheless, corresponding points defined as above will not point in the same direction. The result of such orientation processes has, of course, been an improper location of whipstocks in view of the unwarranted assumption as to maintenance of relative orientations corresponding to those occurring when the stem is straight.

It is the object of the present invention to provide a method of orienting a whipstock within a crooked bore hole in which the angular position of the whipstock is adjusted by the turning of the upper end of a drill stem by which it is supported. In accordance with the invention, however, a proper orientation of the whipstock is assured, within, of course, the limits of error arising because of the algebraic accumulation of errors in lining up the various drill stem sections.

It is a further object of the invention to provide such method of orienting a whipstock in which a check is provided upon its position, this being effected by including within the length of the drill stem at its lower end a surveying instrument capable of indicating accurately the azimuthal position of the whipstock while the whipstock is being lowered and set in place. The necessity for accuracy substantially requires that this well surveying instrument should be of gyroscopic character.

Other objects of the invention will be apparent from the following description read in conjunction with the accompanying drawing in which:

Fig. 1 is a diagram showing the considerations involved in corrections for tortuosity;

Fig. 2 is a diagrammatic elevation showing the assembly of the drill stem, well surveying instrument, and whipstock prior to setting; and

Fig. 3 is a view showing the type of record made by a preferred form of surveying instrument.

Referring first to Fig. 1 there is illustrated therein the position which might be assumed by a hypothetical smooth cylindrical drill stem within a bore hole whose center line is a curve in three dimensions; that is, one which does not in its entirety lie within any plane. The usual path of a bore hole formed by rotary drilling is a curve of this character, the rotation of the drill stem promoting the formation of such tortuous path.

- 10 The effective rotation of a drill stem a due to tortuosity may be determined by considering a hypothetical line e drawn along the cylindrical surface of the drill stem parallel to its axis c when the stem is straight. When the stem is lowered in a crooked bore hole the azimuthal position of this hypothetical line relative to the center line will vary depending upon the shape of the hole. If every portion of the stem is to be without torsional strain we can correctly assume that, if at any point we cut the stem by a plane perpendicular to the center line, then the hypothetical line e at its intersection with the plane will be parallel with the center line c at the intersection of the plane and center line.
- 20 This will be recognized as the obvious condition for absence of torsion in a cylinder.

Choosing rectangular axes such that the positive direction of the x axis is horizontally north, the positive direction of the y axis is horizontally east, and the positive direction of the z axis is vertically downward, the center line of the bore hole (or drill stem) may be expressed by parametric equations:

$$35 \quad \begin{aligned} x &= x(s) \\ y &= y(s) \\ z &= z(s) \end{aligned}$$

in which the parameter s is conveniently taken as the distance measured along the drill stem from the surface.

40 By then making certain approximations justified by the fact that a drill stem will never have a small radius of curvature, we obtain for the angle through which the azimuth of the hypothetical line has changed in a clockwise direction looking downwardly, if the bottom of the drill stem is assumed vertical,

$$50 \quad \phi = \int_{s=0}^{s=1} \left(\frac{dx}{ds} \frac{dy^2}{ds^2} - \frac{dy}{ds} \frac{dx^2}{ds^2} \right) ds$$

the angle being measured in radians, and l being the length of the stem.

55 If the lower end of the bore hole is not vertical and terminates, say, at h of Fig. 1, then it may be imagined as continued to verticality at m by being bent in the vertical plane of the inclination and the calculation of ϕ made in accordance with the above formula to give the direction f of the line e relative to the center line c . The position of line e at the actual end h may then be readily found by applying a correction similar to that used for correcting the intercardinal error of a gyroscope. The results of the hypothetical case give, of course, the correction for tortuosity involved in the actual case.

60 From the above it will be seen that knowing completely the path of the bore hole, it is possible to calculate and make correction for the effect of tortuosity which, except for a complete knowledge of the path of a bore hole, would lead to an unknown deviation of the position of the whipstock from that which might offhand be assumed from the azimuthal position of the upper end of the drill stem.

In carrying out the improved method, it is first necessary to make a complete directional survey of the bore hole. This must be done by the use of some instrument which is not in itself affected by errors due to tortuosity, namely, an instrument which contains within itself an element for indicating azimuth. Both gyroscopic and magnetic instruments would satisfy this requirement; but the only type of instrument which is fully reliable is a gyroscopic one due to the 10 errors caused in magnetic readings by mineral deposits or the presence of magnetic bodies artificially present in the bore hole. An accurate survey with no errors due to tortuosity or magnetism may be made by the type of instrument 15 described in the patent to Williston and Nichols, Number 1,960,038, dated May 22, 1934. This instrument photographically records the position of a gyroscope and a bubble at short intervals of time corresponding to relatively short distances along the path of a bore hole. Such instrument may be lowered either on a wire line 20 or a drill stem for the purpose of making the initial survey.

Following the complete determination of the 25 path of the bore hole the tortuosity correction may be made by the use of the formula given above.

It may be pointed out that a survey made by 30 drill stem orientation is of no use particularly in the present case because the effect of tortuosity which it is desired to ascertain causes the determinations by such method of survey to be in error due to this same effect. In other words, the results of such survey would be in error so 35 as to mask the effects of tortuosity. The result of the application of the above formula to the path calculated from such survey would lead to errors of a magnitude corresponding to the magnitude of the tortuosity correction. 40

Following the completion of calculations as above, there is lowered into the bore hole at the bottom of a drill stem an assembly of the type indicated in Fig. 2. This comprises a whipstock 2, which is shown as provided with a chisel-shaped lower end 4. The showing of this type of whipstock is to be understood to be conventional, since the whipstock may be of any well known type involving, for example, an automatic arrangement designed to engage and hold the 50 bottom of the whipstock at the position of a joint in a casing. The whipstock may also be of the type designed to be secured in place by cementing. The type of whipstock here illustrated would be held in place by being forced 55 into the soil at the bottom of the bore hole.

The whipstock is secured by means of a soft metal rivet or pin 6 to an extension 8 of a setting tool 10 which is coupled by means of a sub 60 12 to the outer casing 14 of a battery container which is indicated as filled with a suitable number of batteries 16. This casing is in turn connected by a coupling 18 to the outer casing 20 of a surveying instrument of the type described in the above-mentioned Williston and Nichols patent. This surveying instrument comprises three parts indicated at 22, including a gyroscope, a timepiece and a box level which are arranged to be simultaneously photographed by 65 the use of a motion picture camera making successive exposures at suitably timed intervals. 70

Above the surveying instrument there is provided a coupling 24 provided with mud passages 26, to which coupling there is secured the lower- 75

most section 28 of the drill stem on which the apparatus is lowered.

The surveying instrument is oriented into a known position relative to the whipstock so that, 5 from the readings obtained in the instrument, the final position of the whipstock will be accurately known. This may be conveniently effected in the Williston and Nichols instrument, as will be seen from Fig. 3, which represents the type of photographic record made in the instrument. On this photographic record there appear a gyroscopic pointer 30 moving adjacent a scale 32, the lead 34, which carries current into the vertical gimbal ring of the gyroscope which carries the pointer 30, 10 a watch 36, and a box level including the concentric circular marks indicative of the inclination of the apparatus by reason of the relationship relative to them of a bubble 40, and a line 42 which may be inscribed upon the surface of the 15 box level cover glass.

Either the line 42 or the lead 34 may be used as the zero of reference of the scale 32, or the scale itself may be suitably marked with a zero indication. Whatever this indication may be, it is 20 brought into position bearing a definite relationship to the inclined face of the whipstock. It will be understood, of course, that the box level occupies a fixed angular position in the casing relative to the gyroscope scale. The mark 42 inscribed on 25 the cover of the level is desirable, since, while the lead 34 is generally visible, it is, to some extent, out of focus, being disposed in a plane above that in which the pointer 30 moves.

The box level forms an integral part of the 30 surveying instrument to which reference has been made. It will be obvious, however, that the indications of the box level are not necessary to the carrying out of the method herein described. It is, however, convenient to have this check upon 35 the inclination of the bore hole at the position where the whipstock is set.

The various sections of the drill stem are lined up relative to each other and the surveying instrument and whipstock by the usual process involving the alignment of successive fourbles relative to each other. This may be effected by the well known procedure of attaching targets to the bottoms and tops of the fourbles and sighting these targets, successively moving them upwardly 40 in steps as the drill stem is lowered by fourble lengths. The drill stem may be turned to secure proper alignment, or, alternatively, the misalignment may be noted and correction made. The process may be carried out either by sighting targets 45 attached to the fourble lengths or by clamping to the fourble lengths telescopes or other sighting instruments directed towards fixed distant objects. This method of orientation of the various lengths to secure a known alignment 50 throughout the entire length of the drill stem is well known and the specific steps involved need not be described herein in detail. It is the same procedure as is frequently followed in making well surveys which, however, as pointed out above, are 55 usually erroneous due to the neglect of the effects of tortuosity of the bore hole. If the hole is initially properly surveyed with a reliable instrument and tortuosity accounted for, then such errors do not enter into the setting of the whipstock.

By the continuation of this process until the whipstock is at the desired depth within the bore hole there is known the relationship of the whipstock to the uppermost fourble for a condition of 60 a straight drill stem; in other words, there is

known in theory a line such as that indicated at e of Fig. 1. As a matter of fact, however, due to tortuosity, the whipstock will be in a position varying from that corresponding to a straight supporting stem by an amount corresponding to the angle given by the above formula following a correction if necessary for intercardinal error. 5

It is desirable at this time to move the drill stem upwardly and downwardly several times to take out any torsional stresses due to friction during its downward passage during which it would probably be turned. This should be done while very carefully maintaining the orientation by sighting as indicated above. 10

The drill stem is then turned in a horizontal 15 direction to bring the whipstock to proper position, the turning being such as to correct for the calculated deflection due to tortuosity. The drill stem is then again moved upwardly and downwardly a number of times to insure the absence of 20 torsional stresses while the new orientation is maintained by sighting. There is now assurance that the whipstock is located in its proper position. 25

In the meantime, the surveying instrument 30 continues to operate to record the actual position of the whipstock, the instrument, as in the patent noted above, being provided with a time-piece which is photographed together with the other instruments so that those records made following the final positioning of the whipstock 35 can be definitely ascertained. A slow timing device is desirably used, in view of the fact that the setting of the whipstock takes considerable time, so that the production of an excessive number of records is avoided. This also serves to relieve the drain upon the batteries, which are then required primarily to furnish only the relatively small amount of current necessary for continuous operation of the gyroscope. 40

The drill stem is now maintained in its fixed azimuthal position and setting of the whipstock is effected. In the use of the type of whipstock shown in the drawing, this is accomplished merely by forcing the bottom end into the soil at the 45 bottom of the bore hole; or, if the bore hole has been partially filled with cement, then into such cement. If another type of whipstock is used, securing of the whipstock in position is accomplished in the suitable fashion. The securing of 50 the whipstock in place may initially be temporary, more permanent securing thereof being obtained by cementing.

After permanent or temporary fixation of the whipstock is obtained, the drill stem is pressed 55 downwardly with sufficient force to shear off the rivet or pin 6, leaving the whipstock free of the lower end of the drill stem, which is then withdrawn, bringing up the surveying instrument. The records of the surveying instrument may 60 then be examined to determine whether the whipstock actually has the proper position. Following the check of this position, drilling may be resumed in any of the usual fashions, for example, as described fully in the article referred to 65 above.

Various details of manipulation need not be described here since they are well known and are brought out, for example, in said article. If the deflection is to take place not in the bottom of a 70 bore hole but at some intermediate position for the purpose, for example, of forming branches, then the various procedures specified in the article may be used to secure the positioning of the whipstock at the proper location. 75

The advantages of the present method are primarily in that it makes possible the correct and accurate setting of a whipstock in a convenient and rapid fashion. The setting of the whipstock 5 is checked and its direction photographically recorded in one round trip of the drill stem. A considerable expense is saved by avoiding a second trip into the hole with a surveying instrument for the purpose of checking the orientation 10 of the whipstock.

It will be clear that variations in the practice of the invention may be made without departing from its scope as defined by the following claims.

What I claim and desire to protect by Letters 15 Patents is:

1. The method of orienting a whipstock within a bore hole including accurately surveying the bore hole to determine its path; lowering the whipstock into the bore hole by means of a sectional drill stem, the sections of which are lined up relatively to each other, and the whipstock being rigidly connected to said sections; orienting the upper end of the drill stem while making allowance for tortuosity of the bore hole to thereby bring the whipstock into a predetermined position; fixing the whipstock in such position; and then withdrawing the drill stem.
2. The method of orienting a whipstock within a bore hole including accurately surveying the bore hole to determine its path; lowering the whipstock into the bore hole by means of a sectional drill stem, the sections of which are lined up relatively to each other, and the whipstock being rigidly connected to said sections, there being lowered with the whipstock an instrument arranged to indicate the azimuthal position of the whipstock, the instrument being adjacent the whipstock and attached thereto; orienting the upper end of the drill stem while making allowance for tortuosity of the bore hole to thereby bring the whipstock into a predetermined position; fixing the whipstock in such position; and then withdrawing the drill stem.
- 30 3. The method of orienting a whipstock within a bore hole including accurately surveying the bore hole to determine its path; lowering the whipstock into the bore hole by means of a sectional drill stem, the sections of which are lined up relatively to each other, and the whipstock being rigidly connected to said sections; orienting the upper end of the drill stem while making allowance for tortuosity of the bore hole to thereby bring the whipstock into a predetermined position, the drill stem being moved up and down during the orienting process to remove torsional stresses; fixing the whipstock in such position; and then withdrawing the drill stem.
- 35 4. The method of orienting a whipstock within a bore hole including accurately surveying the bore hole to determine its path; lowering the whipstock into the bore hole by means of a sectional drill stem, the sections of which are lined up relatively to each other, and the whipstock being rigidly connected to said sections, there being lowered with the whipstock an instrument arranged to indicate the azimuthal position of the whipstock, the instrument being adjacent the whipstock and attached thereto; orienting the upper end of the drill stem while making allowance for tortuosity of the bore hole to thereby bring the whipstock into a predetermined position, the drill stem being moved up and down during the orienting process to remove torsional stresses; recording the azimuthal position of the whipstock in said predetermined position by means of said instrument; fixing the whipstock in such position; and then withdrawing the drill stem.
